LAMP STAND

Edward C. Godfrey, Detroit, Mich.

Application March 26, 1934, Serial No. 717,300

8 Claims. (Cl. 248—126)

This invention relates to an improved supporting stand for a lamp or the like.

An important object of this invention is to provide a stand for a lamp or other object which possesses a pleasing and modernistic design and which is at the same time economical to manufacture.

My improved stand is adaptable for use in different positions. It may be used as a table lamp, being supported upon the table, or as a wall lamp, being secured to a vertical wall.

The immediate support for the light bulb is readily adjustable with respect to the stand to properly function in either a wall or a table lamp or as desired.

An important feature is that my improved stand comprises a base adapted to rest on a table or be secured to the wall and provided with a bulb supporting column extending angularly upwardly from one edge of the base and supporting a light bulb superimposing the center of the base and adjustable from a position normal thereto, to serve as a table lamp to a position of parallelism therewith, to serve as a wall lamp.

A preferred feature of importance is the construction of the preferred form of my improved lamp stand from a rod or a plurality of rod-like elements so fabricated and associated as to provide a novel base having a novel standard or column carrying the lamp bulb. The rods are bent into loops. A plurality of these loops are associated into a base. The ends of the loops are bundled together to form a hollow column extending upwardly and inwardly over the base. A lamp bulb is supported upon the end of this column. The light bulb cord extends through the column.

A preferred arrangement of the loops in the base is in spaced vertical offset inwardly superimposed position, separate loops being formed from separate rods.

The bulb may be mounted upon the end of the column through the employment of a tubular elbow. This elbow is capable of connection with the column to support the bulb in a position normal to the base or parallel to the base. The light cord extends through the elbow and column.

Various other objects and meritorious features of my invention will appear from the following description, appended claims, and accompanying drawings, wherein:

Figure 1 is an elevation of one embodiment of my invention.

Fig. 2 is a plan with the lamp socket and elbow removed.

Fig. 3 is a sectional view on line 3—3 of Fig. 1.

Fig. 4 is a fragmentary sectional view on line 4—4 of Fig. 2.

Fig. 5 is a view of Fig. 4 taken on line 5—5 of

Fig. 4.

Fig. 6 is a cross sectional view through the column of rods at 6—6 in Fig. 1.

Fig. 7 is an elevation, partly in section, showing the manner of mounting a lamp upon the end of the rod column.

Fig. 8 is an elevation of the stand showing the same used as a wall fixture.

Fig. 9 is a plan, partly in section, of a modification of the invention, and

Fig. 10 is an end view, partly broken away, of the modification illustrated in Fig. 9.

Referring to the embodiment of my invention illustrated in the drawings I show a lamp stand having a base 11 and an upright supporting column 12 which carries a light bulb surmounted by a shade 15.

In one preferred embodiment this stand comprises a plurality of rods or rod-like elements each bent or shaped to form a loop 13. The ends of each loop are brought together and bent upwardly and inwardly over the loop. Several rods so bent are associated together to form a stand. The associated loops 13 constitute the base 11 of the stand. The associated inwardly and upwardly bent ends of the loop constitute the bulb supporting column 12 of the stand. The loops of the several rods may preferably be of different dimensions and superimposed in spaced relationship upon one another in the order of their dimensions shown in Figs. 1 and 2.

As illustrated in Figs. 1 to 8, the several loops are offset vertically and horizontally and in spaced relationship.

In these figures a clamp 16 formed of two sections bound together by securing screws or the like maintains the rod loops in spaced offset superimposed relationship. This clamp 16 is illustrated in detail in Fig. 4. It is here shown as arranged at one extremity of the base. The ends of the loops extend upwardly from the opposite extremity of the base. These ends are bundled together to form the supporting column 12 as shown in the several figures. The clamp 16 holds this bundle of loop ends together. These loop ends are so arranged as to form a hollow column through which the electric wire leading to the bulb may extend.

The column extends upwardly and inwardly over the base at an angle of approximately 45°.

The upper end of the column superimposes the center of the base. A light bulb is supported upon the upper end of the column.

This bulb is so supported as to be capable of adjustment to a plurality of positions with respect to the column.

It has one position of adjustment wherein it is upright or disposed normal to the base to enable the structure to serve as a table lamp.

It has another position of adjustment wherein it is disposed in parallelism with respect to the base to enable the structure to serve as a wall light.

One suitable means for accomplishing this adjustment and maintaining the bulb at different

positions of angularity with respect to the column is illustrated in the figures of the drawings. This means comprises an elbow 22 which forms an angular extension of the upper end of the column 12. This elbow is a tubular element and is shaped interiorly at its lower end to be received over the upper end of the column 12 fitting closely about the rod ends or wires which make up the column. These rod ends may be brazed or otherwise secured together. The elbow when fitted over the end of the column will maintain its position thereon. It is detachably receivable over the end of the column so that it may be removed and swung to another angular position with respect thereto and then fitted over the end of the column in this new position.

Two positions are illustrated in the drawings. An upright position normal to the bottom or the plane of the base is shown in Figure 1. A second position of substantial parallelism with the plane of the base is shown in Fig. 8. In the position of Fig. 1 the lamp is adapted for use as a table lamp. In the position of Fig. 8 the lamp is adapted for use as a wall lamp.

25 The elbow 22 is further provided with a tubular axial extension 24 through which the electric light wire 20 extends. This tube 24 is receivable within the interior of the upper end of the column 12 as shown in Fig. 7. It protects the electric wire and facilitates the elbow as an extension of the upper end of the column.

This elbow is interiorly threaded at its upper end to receive a light bulb socket 26 as shown in Fig. 7. A suitable light bulb 14 is carried by the socket. A shade 15 may be mounted upon the bulb.

In order that the stand may also be utilized as a wall light clamp 16 is provided with an undercut slot 17 adapted to receive the head of a nail or other wall attachment as shown in Fig. 8 whereby the stand may thus be suspended from the wall for use as a wall light.

In the embodiment of Figs. 9 and 10 a plurality of rods similarly shaped are fastened together in a somewhat different manner. In this construction the rod loops are arranged in superimposed contacting relationship rather than in spaced apart relationship. Five loops are here shown as making up the base instead of the three loops shown in Fig. 2. Obviously, however, any number of loops may be employed.

55 Clamps 28 are provided to secure the loops together. These clamps are of a somewhat different construction but serve the same purpose as clamp 16 heretofore described. If desired they might be brazed to the loops. Three clamps are here shown, and as here shown they are secured at their upper ends to a plate 30 which forms a cover plate provided with suitable convenient receptacle depressions. In the lower end of each clamp is a U-shaped leg element 32 fitted with cushion insertions 34. The ends of the loops may all be collected together to form a column as shown in the first eight figures of the drawings or certain of these loop ends may stop short and only a limited number thereof be bundled together to form the column as shown in Figs. 9 and 10.

In lieu of the cover plate 30 shown in Figs. 9 and 10, I have illustrated a sliding plate 36 in Figs. 1 and 2. This plate has a receptacle depression for ashes or the like. It has a sliding fit on the top loop 13 for adjustable movement thereof. It may be used or may be omitted as desired.

What I claim:

1. A lamp stand comprising a plurality of rods bent to form individual loops of varying dimensions lying in parallel planes superimposing one another in order of their dimensions, the end portions of said rods adjacent their loop portions being bundled together into a column, said column being bent with respect to the planes of said loops to angularly overlie the same. 5

2. A lamp stand comprising a plurality of rods looped together at one portion of their lengths to form the base of the stand and bundled together in substantially straight parallel relationship at the termination of said looped portions and bent with respect thereto to form an 10 upright supporting column. 15

20 3. A lamp having a stand adapted to support the same as a table lamp or a wall light, said stand comprising a plurality of rods looped at one portion of their length to form the base of the table lamp or the wall engaging face of the wall light, said rods being joined collectively together at another portion of their lengths to form a column bent with respect to the loop portions and maintained by the latter in erect position, and means spacing said looped portions from one another adapted to also serve as a fastening device for securing the stand to a wall. 25

30 4. A lamp stand comprising a plurality of rod-like elements bent into the form of loops, said loops arranged in superimposition forming a base, means securing said loops together, said loops terminating in straight rod-like sections assembled together to form a hollow column said column extending from one side of the base upwardly and inwardly thereover and an angular bulb carrying element secured to the end of said column and adjustable to project upwardly therefrom or substantially parallel to the base. 35 40

5. A lamp stand having a base and a light bulb carrying column formed of a plurality of rod sections joined compactly together in substantially straight parallel relationship and providing a hollow interior through which an electric light cord may run, and a light bulb carrying element mounted on the end of said column and adjustable to varying positions of angularity with respect thereto. 45

6. A lamp stand comprising a plurality of rods joined together in substantially straight parallel relationship to form a light bulb carrying column, said rods being looped at the base of the column and extending angularly with respect thereto to form a supporting base for the column. 50

7. A stand comprising, in combination, a base formed of rod sections bent into the form of loops, and an upright column joined to said base and formed of rod sections bundled compactly together in substantially straight parallel relationship. 55

8. A lamp stand adaptable for support upon horizontal and vertical supports comprising a base and a lamp carrying column secured thereto, said base having a series of substantially oval-shaped, rod-like elements superimposing one another in spaced relationship, said lamp carrying column being joined to the rod-like elements at one end of their oval-shaped formation and inclined to overlie the base, and means adjacent the other end of said oval-shaped elements for supporting the same in spaced superimposing relationship, said means also adapted to serve as a fastening device for securing the base to a vertical support. 60 65 70
